(57) **CLAIM**

The ornamental design for a product package for absorbent article, as shown and described.

DESCRIPTION

FIG. 1 is a front view of a first embodiment of a product package for absorbent article, showing our new design; FIG. 2 is a right side view of the embodiment of a product package for absorbent article shown in FIG. 1; FIG. 3 is a left side view of the embodiment of a product package for absorbent article shown in FIG. 1; FIG. 4 is a rear view of the embodiment of a product package for absorbent article shown in FIG. 1; FIG. 5 is a top view of the embodiment of a product package for absorbent article shown in FIG. 1; FIG. 6 is a bottom view of the embodiment of a product package for absorbent article shown in FIG. 1; FIG. 7 is a front view of a second embodiment of a product package for absorbent article, showing our new design; FIG. 8 is a right side view of the embodiment of a product package for absorbent article shown in FIG. 7; FIG. 9 is a left side view of the embodiment of a product package for absorbent article shown in FIG. 7; FIG. 10 is a rear view of the embodiment of a product package for absorbent article shown in FIG. 7; FIG. 11 is a top view of the embodiment of a product package for absorbent article shown in FIG. 7; FIG. 12 is a bottom view of the embodiment of a product package for absorbent article shown in FIG. 7; FIG. 13 is a front view of a third embodiment of a product package for absorbent article, showing our new design;

(Continued)

FIG. 14 is a right side view of the embodiment of a product package for absorbent article shown in FIG. 13;
 FIG. 15 is a left side view of the embodiment of a product package for absorbent article shown in FIG. 13;
 FIG. 16 is a rear view of the embodiment of a product package for absorbent article shown in FIG. 13;
 FIG. 17 is a top view of the embodiment of a product package for absorbent article shown in FIG. 13; and,
 FIG. 18 is a bottom view of the embodiment of a product package for absorbent article shown in FIG. 13.
 In the drawings the broken lines are for the purpose of illustrating environmental structure only and forms no part of the claimed design.
